[57] CLAIM

The ornamental design for a solar collector panel, as shown and described.

DESCRIPTION

FIG. 1 is a top plan view of a solar collector panel showing my new design;

FIG. 2 is a right side elevation thereof;

FIG. 3 is a left end view thereof; and,

FIG. 4 is a right end view thereof.

The bottom plan view is identical to the top plan view and the left side elevation is identical to the right side elevation.

FIG. 4
